CLAIM

The ornamental design for a cover for transport refrigeration unit, substantially as shown and described.

DESCRIPTION

FIG. 1 is a perspective view of a cover for transport refrigeration unit showing our new design;

FIG. 2 is a front elevational view thereof;

FIG. 3 is a top plan view thereof;

FIG. 4 is a left side elevational view thereof;

FIG. 5 is a right side elevational view thereof; and

FIG. 6 is a cross sectional view taken on line 6—6 of FIG. 2.

The fragmentary broken line representation of the front of a trailer in FIG. 1 is for purposes of illustration only.
